UNITED STATES PATENT OFFICE

HARVEY R. STANDLEE, OF TULSA, OKLAHOMA, ASSIGNOR TO THE GUIBERSON CORPORATION, OF DALLAS, TEXAS, A CORPORATION OF DELAWARE

OIL SAVER

Application filed October 28, 1929. Serial No. 402,851.

This invention relates to new and useful improvements in oil savers.

One object of the invention is to provide an oil saver for use on drill cable, rod and the like in connection with oil and gas wells, whereby certain advantageous results are obtained.

A particular object of the invention is to provide improved packing means for embracing a cable or other cylindrical member together with simple and positive packing compressing means including elements working with sufficient leverage to exert ample pressure to quickly compress the packing against varying head pressures.

A further object of the invention is to provide a packing and a guide arranged for ready application to and removal from the cable or other vertically moving member, and involving simple and easily worked parts.

Another object of the invention is to provide an oil saver having its seal packing below its supporting flange, whereby the length of the device is shortened which permits the temper screw to be screwed further down before reclamping a cable.

A still further object of the invention is to provide an oil saver in which the adjustable packing may be quickly and conveniently replaced.

Another object of the invention is to provide a packing member of peculiar construction arranged to equally grip a cylindrical member throughout the length of said packing member and having adjustable means for feeding said packing member to the cylindrical member as it wears.

An important object of the invention is to provide an oil saver having adjustable packing means of a minimum number of working parts of rugged construction, thus providing for efficiency and speed in operation.

A construction designed to carry out the invention will be hereinafter described together with other features of the invention.

The invention will be more readily understood from a reading of the following specification and by reference to the accompanying drawings in which an example of the invention is shown, and wherein:

Figure 1 is a side elevation of an oil saver constructed in accordance with the invention and illustrated as applied to a cable,

Figure 2 is a vertical sectional view of the oil saver taken parallel with Figure 1, 55

Figure 3 is an end elevation of the oil saver,

Figure 4 is an elevation of the opposite end to Figure 3 showing the oil saver partially dis-assembled for application to a cable, 60

Figure 5 is a plan view of the oil saver,

Figure 6 is a horizontal cross-sectional view taken on the line 6-6 of Figure 1,

Figure 7 is a cross sectional view taken on the line 7-7 of Figure 2, 65

Figure 8 is a perspective view of the working packing,

Figures 9, 10 and 11 are views of the working packing holders.

Figure 12 is a perspective view of one of 70 the wedge blocks,

Figure 13 is an elevation of one of the wedge block adjusting screws,

Figures 14 and 15 are views of the removable pulley housing, 75

Figure 16 is a perspective view of one of the shoes displaced by the wedge blocks, and

Figure 17 is a perspective view of one of the follower links.

In the drawings the numeral 10 designates 80 a split housing. The housing includes a removable lower member 10' secured thereto by bolts 11 and nuts 12. The bolts 11 are mounted in flanges 13 extending from a reduced neck 14 of the housing. Suitable packing strips 15 (Figure 4) are interposed between the housing members.

The housing includes an upper packing chamber A immediately above the reduced neck 14, and a lower packing chamber B. A 90 horizontal annular flange 16 for suitably supporting the device in a casing head extends from the bottom of the neck. The lower packing chamber will be below the top of the casing head and thus the projection of the device above said head will be greatly reduced.

The lower packing chamber has diametrically opposite guides 17 (Figures 2 and 7) which receive sliding wedge blocks 18 rest- 100

ing against upright shoes 19. The shoes (Figure 16) have their rear faces flat to receive the blocks and their front faces concaved to embrace opposite sides of a cylindrical packing member or sleeve 20 fitting in the lower chamber.

Adjusting screws 21 (Figure 13) are threaded through the flange at the same angles as the walls of the guides 17. Each wedge block 18 (Figures 2 and 12) has a key slot 22 for receiving the lower end of one of the screws 21, whereby the blocks are suspended in the guides. By rotating the screws clockwise the blocks are slid downwardly and inwardly thus displacing the shoes 19 inwardly and compressing the packing sleeve about the cable, rod or other element which passes through the device.

The neck 14 has a reduced opening 23 through which the cable C passes and thus said neck forms the top of the lower packing chamber, whereby the sleeve 20 is retained. The upper packing chamber A has cheek plates 24 with opposite horizontal slots 25 for receiving and supporting lugs 26 of followers 27. The lugs slide in the slots and have their outer ends reduced and rounded to form pins 26' for the pivoting thereon of links 28 which have their opposite ends pivoted to levers 29. The levers are pivotally mounted on each side of the housing at the center of the cheek plates on screws 53. The links are pivoted to each lever on opposite sides of its center and so positioned that when each lever is swung upwardly the followers are drawn inwardly toward the center of the housing and the cable C.

The followers 27 are provided with upright dove-tailed grooves 30 for receiving therein a dovetailed rib 31 (Figures 9 and 11) of a rectangular packing block or member 32 (Figure 8). The packing block is formed of rubber or any material suitable for the purpose and has a concave vertical face or seat 33 for engaging around the cable. Grease pockets 33' may be provided in the face 33.

It is obvious that the inward movement of the followers will clamp the packing blocks about the cable and by the location of the lugs 26 at the center of the followers 27 the inward pressure will be evenly distributed to the packing blocks causing said blocks to automatically adjust themselves for equal gripping of the cable throughout its length.

A removable guide block 34 is set into the top of the housing on the same side as the removable section 10' and provides for the convenient, easy and quick application of the device to and removal from a cable, rod or the like. The removable guide block 34 rests on shoulders 35 of the housing and has a tongue 36 (Figures 15 and 18) extending down between the cheek plates to the top of the chamber A, thus forming a top guide for the follower and packing. The shoulders

and the tongue 36 are provided with an opening 37 for the insertion of a bolt 38 therethrough and on which a nut 38' is screwed for securing the block to the housing.

A guide roller 39 is mounted in a recess 40 of the block 34 on a shaft 41 secured in said block. A similar guide roller 39' is mounted in like manner in a recess 40' of the housing, directly opposite and in horizontal alinement with the recess 40. Recesses 23 are also provided in the block and housing for the passage therethrough of the cable C which is guided by the rollers into the housing.

Segmental gears 43 are mounted on the levers 29 and are swung by pinions 44 fastened on the opposite ends of a shaft 45 journaled in a yoke 46 extending laterally from the top of the housing. A worm gear 47 is fastened on the shaft 45 within the yoke. A worm screw 49 (Figure 2) meshes with and drives the gear 47 and is journaled on a stud 50 screwed into the housing above the yoke.

A hold down keeper 51 secured to the yoke bridges over the hub of the worm screw 49 and a crank handle (Figure 1) 52 engages on the angular end of the screw for revolving the same on the stud 50 and thus operating the gears 43. The segmental gears each have their teeth terminating so that when the pinions 44 engage in the uppermost teeth the parts will be locked against further movement except in a reverse direction, thus holding the followers against accidental displacement from within the chamber A.

It is obvious that by revolving the crank handle 52 the shaft 45 is rotated and the segmental gears are swung and as they are swung the links pull the followers inwardly, thus compressing the packing against the cable C. After continued use and when the pinions reach the lowermost teeth on the segments, the packing will have been completely worn out and further inward movement of the followers will be prevented. The operator will thus know that the packing must be replaced.

When it becomes necessary to replace the upper packing 32 it is merely necessary to remove the screws 53 to displace the levers 29 and the links 28 thus leaving the followers free for removal from the housing and for renewing the packing in the followers. In replacing the upper packing the parts are manipulated to bring the segmental gears to the position shown in Figure 1.

It will be seen that by reason of the worm gearing and comparatively large segments considerable leverage is had and therefore the levers 29 will compress the packing 32 with ample force. The device may be easily and quickly operated and as it is only necessary to handle five bolts (38, two 11's and two 53's) the saver may be quickly mounted or dismounted.

Various changes in the size and shape of the different parts, as well as modifications and alterations, may be made within the scope of the appended claims.

5. What I claim, is:

1. In an oil saver, a housing having a vertical packing chamber, compressible packing members located in the packing chamber and having vertical recesses for receiving a movable element to be packed, followers connected with the packing members, levers pivoted on opposite sides of the housing, links pivoted to the followers and also pivoted to the levers, gear segments attached to the levers, and an operating gearing connected with the segments.

2. In an oil saver, a housing having a vertical packing chamber, compressible packing members located in the packing chamber and having vertical recesses for receiving a movable element to be packed, followers connected with the packing members, levers pivoted on opposite sides of the housing, links pivoted to the followers and also pivoted to the levers, segments attached to the levers, pinions meshing with the segments, a shaft journaled on the housing and upon which the pinions are fastened, a worm gear mounted on the shaft, a worm screw meshing with the worm gear, and means for revolving the screw.

3. In an oil saver, a vertical housing having a support and provided with an axial passage, a packing below the support for engaging an element passing through the housing, followers mounted above the support for transverse movement in the housing, packing members carried by the followers for gripping an element passing through the axial passage, and a common operating means for actuating the followers in unison.

4. The combination set forth in claim 3 with a wire line guide at the upper end of the housing including a pair of guide rollers, one of which is removable.

5. In an oil saver, a vertical housing having a support and provided with an axial passage, a packing below the support for engaging an element passing through the housing, followers mounted above the support for transverse movement in the housing, packing members carried by the followers for gripping an element passing through the axial passage, the housing having transverse openings, guides on the followers engaging in said housing openings, levers pivoted on the sides of the housing, links pivotally connecting the levers and the guides, gear segments on the levers, and a train of gearing engaging said segments.

6. In an oil saver, a housing having a vertical passage, packing members mounted to slide transversely in said housing on opposite sides of said passage, followers attached to said members, swinging elements mounted

on each side of the housing and pivoted thereto at their inner ends, links pivoted to each swinging element on opposite sides of the pivot of the latter and connected at their outer ends with the followers, gear segments on the outer ends of the swinging elements, pinions journaled on the housing and meshing with the gear segments, and means mounted on the housing for rotating said pinions to swing said elements.

7. The combination set forth in claim 6, with the packers having vertically elongated narrow faces provided with seats for engaging a cylindrical member passing through the housing, and guides on the followers engaging in the housing for supporting the followers and packers in their sliding movements.

8. In an oil saver, a housing having a vertical packing chamber and a vertical passage extending through said chamber, compressible packing members located in the chamber of the housing on each side of said passage and having vertical recesses for receiving an element extending through said passage, followers connected with the packing members, links on each side of the housing having their outer ends pivoted to the followers, levers pivoted at their inner ends to the sides of the housing, the links having their inner ends pivoted to the levers on opposite sides of the pivots of said levers but close thereto, segmental gears on the outer ends of the levers, pinions mounted on the housing and engaging said gears, means for rotating said pinions, and means for guiding the followers within the housing.

9. An oil saver as set forth in claim 8 in which the sides of the housing are vertical and flat, whereby the segmental gears and the levers may swing freely in close proximity thereto.

In testimony whereof I affix my signature.

HARVEY R. STANDLEE.
